UNITED STATES PATENT OFFICE

1,957,409

LOCOMOTIVE STOKER

Nathan M. Lower, Tuckahoe, N. Y., assignor to
The Standard Stoker Company, Incorporated,
a corporation of Delaware

Original application July 2, 1928, Serial No.
289,774. Divided and this application Decem-
ber 23, 1933, Serial No. 703,763

7 Claims. (Cl. 198—15)

My invention relates to mechanical stokers, and especially pertains to stokers for locomotives and the like.

This application is a division of my co-pending application, Serial No. 289,774, filed July 2, 1928, for Locomotive stoker, now Patent 1,947,723.

In the United States Letters Patent No. 1,711,466 granted April 30, 1929 to E. A. Turner, there is disclosed a locomotive stoker in which the fuel is fed by means of a conduit disposed beneath the floor of the tender into a riser conduit which slopes upward to the lower part of the firing opening of the firebox, a conveyor screw being disposed in such riser conduit so as to deliver the fuel easily and without material pressure or relative movement of its particles to a distributor plate within the firing opening, whereby easy feeding is obtained and breakage of the fuel into undesirably small particles is materially reduced. It is one object of my invention to improve upon stokers of this type by decreasing the necessary upward slope of the riser conduit, and, in general, to provide a stoker having a conduit device extending from the firebox of the locomotive to a position beneath the tender, in which the upward slope of such conduit device to the firebox is reduced to a minimum, thereby facilitating the feeding of fuel through such conduit device and further providing against the breakage of the fuel into undesirably small particles.

Others of my objects, among which are to provide for easy driving of the fuel conveying device in spite of material angularity of parts thereof with respect to each other and to obtain a free flow of fuel through the conduit device, in spite of bends therein, will appear from the following specification taken in connection with the claims annexed thereto.

While, without exceeding the scope thereof as defined in the appended claims, my invention may be embodied in numerous constructional forms, I have described one form thereof, by way of example, in the following specification, and shown the same in the accompanying drawings, in which

Fig. 1 is a plan of a locomotive stoker constructed in accordance with my invention, shown as applied to a locomotive, the firebox of which is indicated in section, the locomotive cab deck and the tender being omitted;

Fig. 2 is a sectional elevation of the stoker shown in Fig. 1;

Fig. 3 is an enlarged plan, partly in section, of the front or outlet portion of the stoker;

Fig. 4 is a sectional view of the rear portion of the stoker, disposed beneath the tender, the section being taken on the line IV—IV of Fig. 1;

Figs. 5 and 6 are an elevation and a plan, respectively, of the universal joint between the fuel conveying members of the stoker;

Fig. 7 is a section on the line VII—VII of Fig. 6;

Fig. 8 is a plan view of the power drive mechanism with some parts in section and other parts removed to best illustrate the construction;

Fig. 9 is a section taken on the line 9—9 of Fig. 8;

Fig. 10 is a section taken on line 10—10 of Fig. 8;

Fig. 11 is an elevation of the clutch drive with the cover removed showing the ratchet wheel and pawl mechanism; and

Fig. 12 is a section taken on the irregular line 12—12—12 of Fig. 8.

The form of stoker herein chosen for description and illustration comprises a tender conduit, the rear portion, 2A, of which is trough shaped and is disposed beneath the fuel hopper 10 of the tender. The conduit is mounted so as to be capable of sliding longitudinally with respect to the tender, as by securing the conduit to a slide 2B (Fig. 4) movably mounted in a longitudinal guideway 10A secured to the tender frame. 85

The front end 2E of the tender conduit is enlarged, at 2D, and is formed, beyond such enlargement, so as to produce the ball member 2C of a hollow ball and socket joint. In effect the hollow portion of the ball member 2C constitutes a part of the enlarged internal end portion of the conduit. This enlarged internal portion should be at least approximately coextensive in length with the width of the external spherical surface of the ball member. This ball member 2C enters a corresponding socket portion 8 formed at the rear end of a riser conduit 3, a removable cap 38 being associated with the socket portion 8 to complete, with the latter and the ball portion 2C, a ball and socket connection between the tender conduit and the riser conduit 3. 95

The front end of the riser conduit 3 is formed with flanged portions 28 by means of which it is secured to a box shaped casting 31 which is attached by means of a flange 31A to the backhead of the locomotive firebox 1 at the lower part of the firing opening 2 of the latter. In this manner, the box shaped casting 31 and the riser conduit 3 form, in effect, a single continuous feed conduit. The lower part of the casting 31 is open, and has 100 105 110

secured therein, by means of cap screws 29, a second casting 32. This second casting 32 is formed with a flat portion constituting a delivery table 22 which is in alignment with the riser conduit 3, and constitutes a continuation of the lower part of the latter, the casting 32 being of such size, and so disposed, that the delivery table 22 extends materially within the inside face of the backhead of the firebox.

- 10 The casting 32 is stepped down, at the front end of the delivery table 22, so as to provide a jet head 6, and is formed beyond such jet head with a shelf constituting a distributor plate 5. The casting is cored out so as to provide right and left hand steam chambers 23 and 23A from which jet openings 6A in the jet head 6 open. The chambers 23 and 23A, through their extensions or passages 24, 24A which open laterally as at the threaded opening 24B, communicate with steam pipes not shown, but which should be provided with suitable control valves, so that steam can be admitted to the jets on either side of the jet head 6 to a greater or lesser amount, thereby determining the extent to which fuel will be fed to one side of the firebox or the other. That portion of the delivery table 22 within the firing opening 2 of the furnace is of greater width than the portion thereof disposed in the casting 31 to permit the fuel to spread laterally before passing over the jet head 6.

A fuel conveyor screw 7 is rotatably mounted in the tender conduit, and is driven from its rear end, through gearing 7A by means of a flexible shaft 7B connected by a telescopic and universal joint with a power drive mechanism 40 which will be hereinafter described in detail. The tender conveyor screw 7 is connected, by means of a universal joint, with a second conveyor screw 4 which is rotatably mounted in the riser conduit 3 and extends beyond the front end of the latter into the casting 31 so as to enter the firing opening 2.

The power drive mechanism 40 comprises a motor of the single cylinder type, the cylinder 70 of which houses a piston 15 which is reciprocable therein to operate a piston rod 71. Secured to the piston rod 71 is a rack gear 41 which is mounted to reciprocate in a housing 40a. At a point remote from the cylinder 70, the housing 40a is apertured and a gear 42 is disposed in the apertured portion and is engaged by the rack gear 41. A cover casting 49 is secured to the top portion of the rack housing 40a to form a closure for the rearward side of said housing 40a which is open to permit machining thereof. A portion of this cover casting 49 also fits over the gear 42 and forms a portion of a bearing 72 for the shaft 61 on which the gear 42 is mounted. A second cover casting 60 is placed over the gear 42 and the shaft 61 and is bolted securely to the first named cover casting 49 and forms therewith a casing for the gear 42 and the other portion of the bearing 72 for the shaft 61.

The shaft 61 extends rearwardly of the gear 42 toward the tender and lies transversely to the rack gear 41. On the rearward portion of the shaft 61 a ratchet wheel 43 is mounted and is engaged by pawls such as 44 carried by the pawl casing 45. As the rack gear 41 reciprocates in the housing 40a, the gear 42 rotates first in one direction and then in another direction. Motion is transmitted to the pawl casing 45 during one stroke of the piston 15, while during the other stroke, the pawl casing 45 idles. The direction of rotation of the pawl casing 45 is determined by

the setting of the pawls 44; the setting of these pawls may be changed at will by the cam shifting collar 16 (Figure 10). The pawl casing is covered by a plate 73 which is firmly secured to the pawl casing 45 and has formed therewith lugs 62 which form one element of a universal joint 74 for driving the flexible shaft 7b. The power drive mechanism 40 passes underneath the riser conduit 3 transversely to the locomotive and is rigidly secured to the frame F by suitable bolts passing through the flanges 48 and 56 of the housing 40a and the cover casting 49 respectively. The power drive mechanism is not secured to the riser conduit 3 in any manner and thus whenever it is necessary to overhaul or repair the drive mechanism, it is only necessary to loosen the bolts which hold the drive mechanism to the frame F. Such a construction greatly expedites repair work and is of great benefit to the railroads in properly maintaining the stoker in a good state of repair.

The fuel, previously broken up into lumps of convenient size by means of a suitable crushing device such as that indicated at 20 (Fig. 2), is fed by the conveyor screw 7 through the tender conduit to the rear end of the riser conduit 3, wherefrom it is picked up by the conveyor screw 4 and carried through the riser conduit 3 to the delivery table 22. When the fuel arrives upon the delivery table 22 it spreads sidewise into a relatively flat stream and flows over the jet head 6 and onto the distributor plate 5. The steam issuing from the jet openings 6A impels the fuel forward into the firebox so as to distribute it evenly over the bed of fuel in the latter.

By locating the distributor plate 5 at a suitable vertical position in the firebox, I am enabled to obtain a proper spreading of the fuel in the latter. At the same time, by placing the distributor plate substantially within the firebox, and sloping the delivery table 22 downwardly and rearwardly therefrom, the height, above the cab deck, of the joint between the riser conduit 3 and the casting 31 is lessened, and I thus accomplish a reduction of the upward slope of the riser conduit. In this way I have made it possible to mount the riser conduit in a position in which it is more nearly horizontal than could otherwise be the case. This permits an easier feeding of the fuel and lessens the relative movement of the particles thereof, as well as the pressure to which such particles are subjected, thereby improving the operation of the stoker, and reducing the tendency of the feeding action to break up the fuel into undesirably small particles. Moreover, the riser conduit passes through the cab deck at a point nearer the front of the latter, thus leaving more floor space available at the back of the cab deck. At the same time, the low level of the front end of the riser conduit makes for specially convenient hand-firing, it being remembered that the fireman, when firing by hand, must shovel the fuel over the riser conduit. Another advantage of the construction is that by providing the extended upwardly sloping delivery table, the use of a conveyor screw which reaches well into the firing opening is facilitated, so that the fuel can readily be moved bodily to a position wherefrom it falls naturally onto the distributor plate.

The universal joint for connecting the conveyor screws 7 and 4 is shown in Figs. 5 to 7. The screws 7 and 4 are forked at their ends to receive pins 34 and 35 respectively. Upon these pins are mounted blocks which in turn are pivoted between a pair of link members 36 and 36A adapted to be

connected together by means of a bolt 69. The member 36A is formed with a tongue 37 which enters a corresponding groove of the member 36, thereby to prevent twisting of one of the link members with respect to the other. The universal joint, as thus constructed, permits an easy driving of the screw 34 from the screw 37, in spite of the angularity between the screws, which may necessarily be increased in applying the stoker to locomotives in which the firing opening is located at a higher level than is here illustrated.

As has been stated, the front end of the tender conduit is enlarged at 2D. The rear end of the riser conduit, 3, adjacent the socket portion 8, is likewise enlarged, as shown at 3A, the conveyor screws 7 and 4 being increased at 7A and 4A, respectively, to accord with the increased diameter of the conduits at these points. By this construction, a free flow of fuel, without jamming and without undue breakage of the particles thereof, is obtained through the joint between the tender conduit and the riser conduit 3, in spite of the extra space taken up by the rotating universal joint. It will be noted the gradual tapering of the conduits in opposite directions from their adjacent enlarged end portions to the smaller conduit portions greatly facilitates this smooth flow of the fuel. In some instances the screw enlargement as at 4A without the enlargement at 7A will be found sufficient to maintain this free movement.

In order to control, with special ease and accuracy, the distribution of the fuel in the firebox, I provide a pair of guide wings or deflector vanes 25, one of which is pivoted to the casting 31 at each side of the outlet opening of the latter. The position of the wings 25 can be adjusted by means of hand wheels 30 which are screwed upon stems 30A pivoted to the deflector vanes. As stated, the fuel is fed forwardly on the delivery table 22 in relatively flat form. By suitable manipulation of the wheels 30, the stream of fuel can be made to flow onto the distributor plate 5 either substantially over the center of the latter or to a greater or lesser extent over the sides as well as the center. Or the fuel can be made to flow onto the distributor plate 5 more to one side of the latter than to the other. By this means, as well as by the adjustment of the amount of steam supplied to the chambers 23 and 23A, the fuel can be distributed properly in the firebox in accordance with such different conditions as may obtain from time to time.

The delivery table and distributor plate are cooled to a large extent by the steam in the relatively large steam chambers 23, 23A. In order to provide further means for cooling the casting 32, the latter is disposed so as to provide a passage 27B between its lower part and the bottom side of the firing opening 2, and is formed with a hollow downward extension 27A, the interior of which is open to the atmosphere and communicates with the passage 27B. Air is induced through the passage 27B by the draft from the stack, and impinges against the casting 32 to prevent overheating of the lower part thereof, including the distributor plate 5. When the stack draft is cut off, the extension 27A has a chimney effect, so that air continues to be drawn past the lower part of the casting 32 and smoke does not emerge into the cab. Jets 27, for assisting in inducing air through the passage 27B, particularly when the stack draft is cut off, are formed in the casting 32 at the rear of the passage 27B.

In order to cool the front end of the conveyor

screw 4, as well as to provide means permitting inspection of the interior of the outlet end of the stoker, the casting 31 is formed with a plurality of slotted openings 65 in the upper part thereof, a slide 66 being provided for varying the size of the openings, or closing them if desired. In order, also, to cool the guide wings 25, the flange 31A of the casting 31 is formed with air openings 67 through which air is drawn so as to impinge against the wings 25 and cool the latter.

The stoker of my invention is a material improvement over previous constructions in that it permits the fuel to be fed from beneath the tender up to and into the firing opening with a minimum of upward slope of the conduit device. Because of this, the fuel is moved easily, with a minimum of pressure between the particles thereof and with a minimum of relative movement of such particles. In this way the proportion of dust and fine particles, produced by abrasion in the fuel during the feeding thereof, is greatly reduced, and a very smooth and efficient feeding action is obtained. Another important advantage is that the distribution of the fuel in the firebox is exceptionally uniform and efficient, and that the control thereof, to place the fuel at various desired positions in the firebox, is specially complete and convenient. Furthermore, the construction of the universal joint employed permits easy driving of one conveyor screw from the other in spite of material angularity between them, and the construction of the conduit allows a free flow of the fuel regardless of the additional space taken up by the rotating universal joint.

I claim:

1. In a conveying system, a pair of conduits, a universal joint structure flexibly connecting the adjacent ends of said conduits, a ball member formed at an end of one of said conduits and having an outer spherical surface constituting one element of the universal joint structure, such conduit having an internal surface tapering inwardly toward the axis of the conduit from the named end thereof, said tapering internal surface being at least approximately coextensive in length with the outer spherical surface of said ball member, and a socket formed with an adjacent end of the other conduit, said socket having an internal spherical surface forming a seat for the ball member of the first named conduit, the second named conduit having a portion tapering inwardly from adjacent the aforesaid end of said conduit.

2. In a conveying system, a pair of conduits, a universal joint structure flexibly connecting the adjacent ends of said conduits, a ball member formed at an end of one of said conduits and having an outer spherical surface constituting one element of the universal joint structure, such conduit having an internal surface tapering inwardly toward the axis of the conduit from the named end thereof, said tapering internal surface being at least approximately coextensive in length with the outer spherical surface of said ball member, said conduit having a straight portion extending from the reduced end of the tapering internal surface, a socket formed with an adjacent end of the other conduit, said socket having an internal spherical surface forming a seat for the ball member of the first named conduit, the second named conduit having a portion tapering inwardly from adjacent the aforesaid end thereof and a straight portion extending from the reduced end of said tapering portion.

3. In a conveying system, a pair of conduits, a universal joint structure flexibly connecting

- the adjacent ends of said conduits, a ball member formed at an end of one of said conduits and having an outer spherical surface constituting one element of the universal joint structure, such 5 conduit having an internal surface tapering inwardly toward the axis of the conduit from the named end thereof, said tapering surface being at least approximately coextensive in length with the outer spherical surface of said ball member, 10 said conduit having a straight portion extending from the reduced end of the tapering internal surface, the second conduit being angularly disposed with respect to the first named conduit, a socket formed with an end of the second named 15 conduit adjacent the first named conduit, said socket having an internal surface forming a seat for the ball member of the first named conduit, the second named conduit having a portion tapering inwardly from adjacent the aforesaid 20 end thereof, a straight portion extending from the reduced end of said tapering portion, and a flexible conveyor in said conveying system, including a conveyor screw in the first named conduit, a conveyor screw in the second named conduit, each conveyor screw being provided with a 25 forked jaw terminating adjacent the tapering surface of said ball member, and a link connecting the forked jaws and constituting one element of a universal joint connecting the named screw 30 conveyor.
4. A stoker riser conduit of tubular formation having a fuel receiving end and a fuel delivery end constructed with its bottom wall terminating short of its side walls at said delivery 35 end to form in said end an opening in the bottom of the conduit extending from one side wall to the other, said conduit having a spherical seat formed at its fuel receiving end, a straight portion included between said seat and said opening 40 and a tapering portion intermediate said seat and said straight portion of the conduit.
5. A stoker riser conduit of tubular formation having a fuel receiving end and a fuel delivery end constructed with its bottom wall terminating 45 short of its side walls at said delivery end to form in said end an opening in the bottom of the conduit between the side walls, said conduit having a spherical seat formed at its fuel receiving end, a straight portion included between said 50 seat and said opening and a tapering portion intermediate said seat and said straight portion of the conduit.
6. In a conveying system, a pair of conduits at their adjacent ends forming a universal joint structure, each conduit being provided with an 55 enlarged end at said joint structure and with a
- smaller portion adjoining said enlarged end, said enlarged end of the one conduit having an external spherical surface forming a ball member constituting one element of the joint structure and including a tapering internal surface tapering from the front face of said ball member toward the said smaller portion of the conduit, the enlarged end of the other conduit including a socket member constituting another element of the joint structure and an internal tapering surface tapering from adjacent said socket member toward the said smaller portion of the conduit, said socket member having an internal surface conforming to the ball member of the first named conduit for forming a seat therefor, a screw conveyor in each of said conduits, the screw conveyor within the second named conduit being arranged with that portion within the enlarged end of the conduit having an enlarged flight portion conforming approximately to the enlarged end of the conduit and arranged with its remaining flights conforming approximately to the smaller portion of the conduit, and a universal joint member connecting the adjacent ends of said screws within the vicinity of the universal joint structure of the conduits. 80 85 90 95 100
7. In a conveying system, a pair of conduits at their adjacent ends forming a universal joint structure, each conduit being provided with an enlarged end at said joint structure and with a 105 smaller portion adjoining said enlarged end, said enlarged end of the one conduit having an external spherical surface forming a ball member constituting one element of the joint structure and including a tapering internal surface tapering from the front face of said ball member toward the said smaller portion of the conduit, the enlarged end of the other conduit including a socket member constituting another element of the joint structure and an internal tapering surface tapering from adjacent said socket member toward the said smaller portion of the conduit, said socket member having an internal surface conforming to the ball member of the first named conduit for forming a seat therefor, a screw conveyor in each of said conduits, the screw conveyor within the second named conduit being arranged with that portion within the enlarged end of the conduit having an enlarged flight portion conforming approximately to the enlarged end of the conduit and arranged with its remaining flights conforming approximately to the smaller portion of the conduit, and a universal joint member connecting the adjacent ends of said screws within the vicinity of the universal joint structure of the conduits. 110 115 120 125 130

NATHAN M. LOWER.
